(57) **CLAIM**

The ornamental design of a position adjustable hook with ball joint collar to be used in hand lamp, as shown and described.

DESCRIPTION

FIG. 1 is a perspective view of a position adjustable hook with ball joint collar to be used in hand lamp, showing my invention;

FIG. 2 is a top plan view of the invention;

FIG. 3 is a bottom plan view of the invention;

FIG. 4 is a rear elevational view of the invention;

FIG. 5 is a left-side elevational view of the invention;

FIG. 6 is a front elevational view of the invention;

FIG. 7 is a right-side elevational view of the invention; and, FIG. 8 is a perspective view of the position adjustable hook with ball joint collar mounted to a hand lamp.

The two arrows around the ball joint demonstrate the hook is position adjustable. The other two arrows around the collar demonstrate the collar is rotatable around the handle of the hand lamp. The broken lines in the drawings illustrate a hand lamp. The arrows and broken lines shown in FIG. 8 form no part of the claimed design.
